UNITED STATES PATENT OFFICE.

ELMER G. GARTIN, OF CLAREMONT, NEW HAMPSHIRE, ASSIGNOR TO SULLIVAN MACHINERY COMPANY, A CORPORATION OF MASSACHUSETTS.

PERCUSSIVE MOTOR.

Application filed June 1, 1920. Serial No. 335,726.

My invention relates to percussive motors and more especially to percussive motors adapted for submarine drilling.

It has for its object to provide an improved percussive motor. A further object of my invention is to provide an improved percussive motor in which improved fluid distribution means is provided. A still further object of my invention is to provide an improved percussive motor for submarine use in which the fluid supply connections may be as simple as possible and, to the maximum degree, leave the workman free from danger of entanglement. Further objects of my invention will appear in the course of the following specification and claims.

In the accompanying drawings I have shown for purposes of illustration one form 20 which my invention may assume in practice.

In these drawings,—

Fig. 1 is a view partially in elevation and partially in central longitudinal section of a motor embodying the illustrative form of 25 my improved construction.

Fig. 2 is an enlarged view of the cylinder taken on line 2—2 of Fig. 4, and showing the piston in one position.

Fig. 3 is a similar view showing the piston approaching the opposite position.

Fig. 4 is a transverse section on the line 4—4 of Fig. 2.

I have chosen for the illustrative embodiment of my invention, a motor of the percussive type which is especially adapted for use in submarine work. In such work, it is requisite that a water tight tool be provided and it is further requisite that the connections shall be as few as possible in order to prevent interference with and entanglement 30 of the workman. Also for work in water of relatively great depth, it is essential that exhaust fluid from the motor be released well above the level of the work or conducted to the surface, as in relatively deep water it is possible that the exhaust pressure may be 35 below the hydrostatic head. In even relatively shallow water in the intervals between exhaust from the opposite ends of the cylinder there would be a tendency for a reverse flow of water into the motor, which would 40 not only considerably retard its operation but might check it entirely as well as injure the finish of the working parts. It will be 45 obvious, however, that my improved con-

struction is not limited to use in submarine work as the construction is well adapted for use also with drills of the so called "ground hog" type.

In the illustrative embodiment, my motor 60 consists of a cylinder 1 provided adjacent its forward end with a housing 2 in which a drill steel is adapted to be retained and which may be, if necessary, provided with a suitable type of water tight packing. The 65 rear end of the cylinder is closed by the head 3 to which a handle member 4 is attached. the cylinder 1, the head member 3, and the handle member 4 being connected by bolts 70 passing through all three of them. The cylinder is provided with a bore 5 in which there is reciprocable, under action of the pressure fluid, a piston 6 provided with a striking bar 7 adapted to impact upon the end of a steel 8 which is received in the 75 housing 2. The piston is bored out at its rear end to provide a cylindrical chamber 10 between the ends of which an annular enlarged groove 11 is formed. Extending forwardly from the groove are several spaced 80 ports 12 communicating with the forward end of the cylinder bore 5 at the front end of the piston. Formed in the exterior periphery of the piston member 6 and angularly spaced between the passages 12 are 85 several shallow grooves 13 which communicate by means of passages 14 with the forward end of the bore 10 of the piston. The cylinder bore 5 adjacent the rear end thereof is provided with an enlarged annular 90 groove 15 adapted to be overrun by the ends of the grooves 13 when the piston is adjacent the rear end of its stroke, and having its forward edge adapted to cooperate with the rear ends of the grooves 13 to control 95 admission and cut off of fluid to the rear end of the motor cylinder. Passing through a bore 20 in the handle member 4 and making a tight fit therewith is a hollow fluid conducting member 21 which extends into the 100 rear end of the cylinder 5 and at its forward end makes a close fit with the interior of the piston bore 10. This member 21 is provided with a central bore 22 for the conduction of live fluid from a suitable supply line 23, and 105 is also formed upon its exterior periphery with a series of spaced grooves 24 extending longitudinally from a point adjacent the front end thereof to a point adjacent the rear thereof where communication is had 110

with the exhaust connection 25. The cylinder head member 3 is provided with a forward extension 26 in which are formed several openings 27 and these openings communicate with the grooves 24 in the fluid conducting member 21. The forward end of the member 26 makes a tight joint with the member 21. The ports 27 cooperate as will hereinafter be described with the passages 24 to conduct the exhaust from both ends of the cylinder 5 to the exhaust connection 25.

The operation of this illustrative embodiment of my improved motor is as follows: Starting with the position of the piston shown in Fig. 2, live fluid is supplied from the passage 23 through the bore 22 to the interior of the chamber 10 and passes thence by way of the passages 14, grooves 13, and annular groove 15 to the rear end of the cylinder and accordingly the piston will move forward under the pressure of live fluid acting upon the circular area, constituting the front end of the bore 10, and the annular area of the back end of the piston. At this time it will be noted that the front end of the cylinder 5 is in communication by means of passage 12, groove 11, port 27 and longitudinal groove 24 with the exhaust connection 25 and accordingly such fluid as may be in the forward end of the cylinder is free to pass to the exhaust. As the piston 6 moves forward, the rear ends of the grooves 13 overrun the forward edge of the annular groove 15 and accordingly the admission of live fluid to the rear end of the cylinder is discontinued. From this moment to the instant when the rear end of the piston overruns ports 27, the piston 6 moves forward under the expansive action of fluid on the rear end of the piston and live fluid acting on the circular area at the front end of the bore 10. When the ports 27 are overrun by the rear end of the piston, exhaust from the rear end of the cylinder takes place and, as prior to that moment live fluid has begun to be conducted to the front end of the cylinder by way of the groove 11 and ports 12, it will be obvious that the forward movement of the piston will speedily be checked and its direction reversed. Upon the return movement of the piston, admission to the front end of the cylinder will continue until the front end of the groove 11 passes beyond the front end of the member 21, at which time cut off will occur and from that moment on the piston will move under the expansive action of the fluid entrapped in the front end of the cylinder until the exhaust ports 27 again communicate with the rearwardly moving groove 11, at which time exhaust from the front end of the cylinder will occur. As soon as the live fluid which at about the same moment is admitted to the rear end of the cylinder, and the live fluid which

has been continuously acting on the circular area of the front of the bore 10, overcomes the momentum of the piston 6, its direction will be reversed and the double cycle of operations described will be repeated.

It will be noted that I have shown a passage 28 extending longitudinally through the striking bar and conducting fluid to the chuck housing and to a hollow steel, if one be used. This expedient prevents danger of leakage of water into the front end of the cylinder when the air pressure is greater than the water pressure and is also of utility when the tool is used as a ground hog, as it supplies means to blow chips to the surface. This passage may obviously be omitted if desired.

From the foregoing description, it will be noted that I have provided a fluid motor having concentrically arranged supply and exhaust means. A single fluid exhaust means for both ends of the cylinder is also provided, and it will also be noted that by means of the concentric arrangement described, a very simple fluid supply and exhaust connection may be made to the motor, the rear ends of the members 21 and 4 being provided with threaded portions for the purpose of permitting attachment to both of the concentric supply and exhaust means.

While I have in this application specifically described one form which my invention may assume in practice, it will be understood that this form of the same is shown for purposes of illustration and that the invention may be modified and embodied in other forms without departing from its spirit or the scope of the appended claims.

What I claim as new and desire to secure by Letters Patent is:

1. A valveless fluid pressure percussive motor comprising a cylinder, a piston reciprocable therein having a constant pressure chamber, and fluid distribution means for effecting reciprocation of said piston comprising concentrically arranged means extending within said cylinder and into said chamber and between which and said piston relative movement occurs for conducting live and exhaust motive fluid respectively to and from both ends of said cylinder.

2. A valveless fluid pressure percussive motor comprising a cylinder, a piston reciprocable therein having a constant pressure chamber, and fluid distribution means for effecting reciprocation of said piston comprising means coaxially disposed with said piston and between which and said piston relative movement occurs and having communication with said chamber for conducting live fluid through said chamber to both ends of said cylinder and for conducting exhaust motive fluid from both ends of said cylinder.

3. A fluid pressure percussive motor com-

prising a cylinder, a piston reciprocable therein provided with a bore within which fluid under pressure is maintained, and fluid distribution means for effecting reciprocation of said piston comprising a fluid supply member projecting into said bore from one end of said cylinder and having telescopic sliding engagement with said piston, and means also formed on said member for conducting exhaust fluid from both ends of said cylinder.

4. A fluid pressure percussive motor comprising a cylinder, a piston reciprocable therein, said piston being provided with a bore within which fluid under pressure is maintained, and fluid distribution means for effecting reciprocation of said piston comprising a member projecting into said bore from one end of said cylinder and relative to which said piston is movable, said member being provided with concentric fluid supply and exhaust passages extending to points outside the cylinder bore, and means on said piston for conducting live fluid to both ends of said cylinder and exhaust fluid from one end of said cylinder.

5. A fluid pressure percussive motor comprising a cylinder, a piston reciprocable therein having a hollow bore within which fluid under pressure is maintained, a member closing one end of said cylinder, a member provided with a grasping portion secured to the same end of said cylinder, and fluid distribution means for effecting reciprocation of said piston comprising an extension formed on said first mentioned member and entering said bore and relative to which said piston is movable, a member formed on said second mentioned member disposed concentrically with respect to said first mentioned member and also extending into said latter member, and concentrically arranged passages in the inner one of said two latter members and between said members cooperating with said piston to distribute live fluid to and conduct exhaust fluid from both ends of said cylinder.

6. A fluid pressure percussive motor comprising a cylinder member, a piston reciprocable therein having a constant pressure chamber, fluid supply means for said motor including a passage forming member relative to which said piston is movable projecting longitudinally into said cylinder and constantly communicating with said chamber in said piston, and exhaust means comprising a passage formed in said member and a port constantly communicating with said passage and adapted to communicate with the interior of said cylinder at the opposite ends of the latter near the end of alternate piston strokes.

7. A valveless fluid pressure percussive motor comprising a cylinder, a piston reciprocable therein having an internal constant

pressure chamber, and fluid distribution means for effecting reciprocation of said piston comprising means concentric with said piston and extending from one end of said cylinder into said internal chamber for conducting exhaust fluid from both ends of said cylinder, said means having telescopic sliding relation with said piston.

8. A valveless fluid pressure percussive motor comprising a cylinder, a piston reciprocable therein having an internal constant pressure chamber, and fluid distribution means for effecting reciprocation of said piston comprising pressure fluid supply and exhaust means concentric with said piston and between which and said piston relative movement occurs, said means including a passage communicating with said internal chamber, and a passageway in said piston communicable with said supply and exhaust means and one end of said cylinder and adapted to discharge exhaust fluid from said cylinder and admit pressure fluid thereto.

9. A valveless fluid pressure percussive motor comprising a cylinder, a piston reciprocable therein having an internal constant pressure chamber, and fluid distribution means for effecting reciprocation of said piston comprising pressure fluid supply and exhaust means including an element extending into said chamber and relative to which said piston is movable, and a passageway in said piston communicable with said supply and exhaust means and one end of said cylinder and adapted to discharge exhaust fluid from said cylinder and admit pressure fluid thereto.

10. A valveless fluid pressure motor comprising a cylinder, a piston reciprocable therein having an internal constant pressure chamber, and fluid distribution means for effecting reciprocation of said piston comprising fluid supply and discharge means for said cylinder including an element projecting into said chamber and relative to which said piston is movable, a passageway in said piston communicable with said supply and discharge means and adapted to admit pressure fluid to or discharge exhaust fluid from one end of said cylinder, and means for supplying fluid pressure to and discharging exhaust fluid from the other end of said cylinder.

11. A valveless fluid pressure motor comprising a cylinder, a piston reciprocable therein having an internal constant pressure chamber, and fluid distribution means for effecting reciprocation of said piston comprising fluid supply and discharge means for said cylinder including an element projecting into said chamber and relative to which said piston is movable, a passageway in said piston communicable with said supply and discharge means and adapted to admit pressure fluid to or discharge exhaust fluid from

one end of said cylinder, and means for supplying fluid pressure to and discharging exhaust from the other end of said cylinder, said latter means having passages adapted to cooperate with said first mentioned passageway.

12. A fluid motor comprising a cylinder, a piston reciprocable therein having an internal constant pressure chamber, and fluid distribution means for effecting reciprocation of said piston including a member extending axially within said piston relative to which the latter is movable and communicating with said chamber for conducting motive fluid to the latter and for conducting the exhaust motive fluid from both ends of said cylinder.

13. A fluid motor comprising a cylinder, a piston reciprocable therein having an internal constant pressure chamber, and fluid distribution means for effecting reciprocation of said piston including a member secured to said cylinder and extending axially within said piston and communicating with said chamber for conducting motive fluid to the latter and for conducting the exhaust motive fluid from both ends of said cylinder.

14. A fluid motor comprising a cylinder, a piston reciprocable therein having an internal constant pressure chamber, and fluid distribution means for effecting reciprocation of said piston including a member having concentric axially extending passages formed therein projecting within said piston and relative to which the latter is movable and communicating with said chamber for conducting motive fluid to the latter and for conducting exhaust motive fluid from both ends of said cylinder.

15. A fluid motor comprising a cylinder, a piston reciprocable therein having an internal constant pressure chamber, and fluid distribution means for effecting reciprocation of said piston including means controlled by said piston and relative to which the latter is movable including a member extending axially within said piston and communicating with said chamber for conducting motive fluid to the latter and for conducting the exhaust motive fluid from both ends of said cylinder.

16. A fluid motor comprising a cylinder, a piston reciprocable therein having an internal constant pressure chamber, and fluid distribution means for effecting reciprocation of said piston including common means including an element projecting into said chamber and relative to which said piston is movable for conducting both the supply of fluid to and the exhaust of fluid from both ends of said cylinder.

17. A fluid motor comprising a cylinder, a piston reciprocable therein having an internal constant pressure chamber, and fluid distribution means for effecting reciprocation of said piston including common means controlled by said piston and including an element projecting into said chamber for conducting both the supply of fluid to and the exhaust of fluid from both ends of said cylinder.

18. A fluid motor comprising a cylinder, a piston reciprocable therein having an internal constant pressure chamber formed therein, and fluid distribution means for effecting reciprocation of said piston including means for maintaining fluid under pressure in said chamber during operation of said piston, and means relative to which said piston is movable including a passage extending within and controlled by a wall of said chamber for conducting the exhaust fluid from the opposite ends of said cylinder.

In testimony whereof I affix my signature.

ELMER G. GARTIN.
